UNITED STATES PATENT OFFICE.

HERBERT E. BRIDGWATER, OF SYRACUSE, NEW YORK, ASSIGNOR TO REMINGTON TYPEWRITER COMPANY, OF ILION, NEW YORK, A CORPORATION OF NEW YORK.

TYPEWRITING MACHINE.

Application filed March 16, 1922. Serial No. 544,161.

To all whom it may concern:

Be it known that I, HERBERT E. BRIDGWATER, citizen of the United States, and resident of Syracuse, in the county of Onondaga and State of New York, have invented certain new and useful Improvements in Typewriting Machines, of which the following is a specification.

My present invention relates particularly to light or portable typewriters of the collapsible or compactible style, and has for its main object to provide new and improved type bar actuating mechanism which is especially adapted for employment in a portable typewriting machine wherein the type bars are collapsible. More specifically stated the object of my invention is to adapt type bar mechanism of the kind disclosed in my prior application Serial No. 532,983, filed January 31, 1922, to a collapsible typewriting machine wherein the type bars themselves are pivoted on a fixed or non-shiftable support as in the well-known Remington portable typewriter.

To the above and other ends which will hereinafter appear, my present invention consists in the features of construction, combinations of devices and arrangements of parts hereinafter described and particularly pointed out in the appended claims.

The preferred form of my present invention is illustrated in the accompanying drawings as applied to the Remington portable typewriter. In said drawings,

Figure 1 is a fragmentary top plan view, with parts in section, of a collapsible portable typewriting machine embodying my invention, only so much of the machine being shown as is necessary to a complete understanding of the invention.

Figure 2 is a fragmentary fore-and-aft vertical sectional view taken about centrally of said machine and approximately on a plane indicated by the section line 1—1 in Figure 1 and looking in the direction of the arrow thereat.

Figure 3 is a fore-and-aft vertical sectional view corresponding to Figure 2 but showing the machine in collapsed or compacted condition, whereas Fig. 2 shows the type system raised and the machine expanded ready for use.

Figure 4 is a fragmentary sectional view showing the central type bar action of Fig. 3 in operated position, the lower case type

being shown in printing contact with the platen.

Figure 5 is a fragmentary transverse vertical sectional view taken on a plane indicated by the section line 2—2 in Fig. 1 and looking rearward in the direction of the arrow at said line, but omitting some of the parts shown in Fig. 2.

In the Remington portable typewriting machine, whose construction corresponds generally with the disclosures in the patent to A. W. Smith, No. 1,342,513, granted June 8, 1920, and J. B. Holden, No. 1,386,256, granted August 2, 1921, the main frame is composed largely of sheet metal, comprising right and left-hand side plates 1 of suitable form, which are connected at the front by a bar or plate 2 provided with parallel kerfs to form a comb plate. Near their rear portions the side plates 1 are connected by a casting 3 which differs somewhat in form from the usual casting of the Remington portable machine, and comprises an inner segmental portion 4, and an outer segmental portion 5 of larger diameter but concentric with the inner segmental portion from which it is spaced apart. Side portions or webs 6 connect the segmental portions 4 and 5 at their ends and extend laterally outward, their end faces receiving headed screws 7 by which the whole casting 3 and the side plates 1 are secured in rigid relationship. An outer sheet metal casing 8 incloses the framework comprising the plates 1 and 2, and the casting 3. A top plate 9 is suitably secured to certain of the frame members, its rear edge being formed on an arc of a circle except at the sides which are straight. The platen 10, which is diagrammatically illustrated, is mounted on a traveling carriage which is shiftable to change case in a direction fore-and-aft of the machine as is usual. A type bar lifter, rest device or support is provided as in the Remington portable machine, said device comprising a type rest proper or pad 11 which may be of felt, and a segment 12 of sheet metal. On top of the segment 12 is arranged a wider segmental plate or dust shield 13, the forward edge of said shield being contiguous to the rear edge of the top plate 9 when the machine is collapsed. Beneath the segment 12 is secured a plate 14 of sheet metal formed with a trough or seat 15 at its rear side which re-

105
110

ceives the rest or pad 11, the latter being confined in the seat by the downwardly bent rear edge of the shield 13. The rest 11 is movable up and down and to this end 5 the outer end portions of the segment 12 are provided with vertical ears or standards 16 which are received in and slidably co-operate with flanged or U-shaped guides 17 vertically arranged and provided at their 10 lower ends with horizontal base-portions 18 secured to the under side of the webs 6 by screws 19. The rest device or lifter is movable to predetermined set positions by means that co-operate with ears 20 bent 15 downward from the ends of the segment 12 and to which are pivotally connected at 21 the upper ends of links 22, said links at their lower ends being pivoted at 23 to crank arms 24 fixed to a rock shaft 25 arranged transversely of the machine in its 20 base, said shaft being rotatably supported on the side plates 1. The hand-controlled means for rocking the shaft comprises a crank arm 26 fixed to the right-hand end of the shaft outside the adjacent side plate 1. The outer end of said crank arm terminates 25 in a laterally projecting head 27 which houses a poppet stud and also supports a convenient finger piece. The housing or head 27 is bored out as indicated at 28 to receive a poppet stud or pin 29 which is provided with a flange 30 and carries outside the housing a cap 31 which fits over the end of the housing and serves as a finger piece 30 for pulling the poppet stud longitudinally outward against the force of its spring 32, and also for adjusting the crank arm 26. The inner end of the stud is adapted to co-operate with two holes 33 formed in the right-hand side plate 1 to lock the crank arm 26 and the parts connecting the rock shaft with the shiftable rest device in set 40 positions. An arcuate slot 8^a in the right-hand plate 8 affords passage-way for the head 27 during swinging movements of the crank arm 26. The crank arms 24 and the links 22 constitute pairs of toggles which are broken when the machine is collapsed as 45 in Fig. 3, but which, when straightened as in Fig. 2 by operation of the finger piece or key 31, elevate the rest 11 and expand the machine. Fixed centrally to the rear portion of the casting 3 by screws 34 is a stationary center guide member 35 which is inclined rearward and slightly upward and terminates in a guide opening indicated 50 at 36 with which the type ends of the type bars are adapted to co-operate as they near the printing point on the top of the platen. Said type bars, each designated by the 55 numeral 37, are arranged in an arc of a circle forward of the platen, being received in vertical slots indicated at 38 formed radially in the front and under portion of the segment 4, these guide slots radiating from

a common center on the type guide 35 at the lower end of the guide opening 36. Only a few of the guide slots or kerfs 38 are illustrated in the drawings but it is to be understood that the segment 4 is cut or formed 70 with a full series of such slots sufficient to receive and guide a complete set of type bars 37. These type bars are mounted on a common arcuate pivot wire 39 which is received and housed in a slot 40 formed horizontally in the upper portion of the segment 4. The free end of each type bar is provided with a type block 41 having two types, one lower case and one upper case, the lower 80 case types co-operating with the platen normally and the upper case types coming into use when the platen is shifted. At the under side of the type bar opposite the type block is a rounded projection or nose 42 which, when the machine is compacted or collapsed 85 as in Fig. 3, may contact with a pad 43 of compressed felt or the like which is secured in a depression or countersink in the top plate 9, said pad being arcuate and extending from one side of the top plate to the other. When thus compacted it will be understood that the machine and the type bars are in a condition of disuse, the body 90 portions of the type bars being recumbent or substantially horizontally disposed and resting between their pivots and their type 95 ends on the rest or pad 11 which is in its depressed or lowermost position. The top corner of the pad proper projects above the 100 surface of the shield 13 and the under edges of the type bars are so shaped that they contact only with the rest 11 and the pad 43 so that when the lifting device 11-15 is 105 raised the type bars will slide freely over the rest or pad 11 which rises vertically. The heel portions of the type bars, or those 110 portions at the opposite sides of their fulcrums from the body portions, curve or extend downward when the type bars are in disused position, said heel portions passing 115 through the guide slots 38. The heel of each type bar is provided with a cam or curved actuating slot indicated at 44. Co-operatively engaging with said slot is a headed 120 actuating pin 45 which projects laterally from the rear end of an operating member or sub-lever 46, said lever underlying the 125 associate type bar and having a yielding or floating support hereinafter more fully described. The sub-levers 46 are levers of the first order and at their forward ends are pivotally connected at 47 with the upper ends of depending links 48, the lower ends of said links being pivotally connected at 49 with printing key levers 50. The pivotal connections 49 are in the form of pins projecting from the sides of the key levers, the links 48 being perforated to fit over said pins and being prevented from becoming accidentally detached by spring clips 51 130

secured to the sides of the key levers 50. Said key levers extend horizontally fore-and-aft of the machine and at their rear ends are formed with open-mouthed slots 52 to fit over and co-operate with a fulcrum rod 53 which is mounted on a slotted angle-bar 54 secured by screws 55 to the under side of the casting 3. Near their front ends said key levers pass through and are guided by the comb plate 2, said key levers terminating in upright portions or stems 50^a which receive finger keys or buttons 56. The stems of the key levers are varied in height so as to provide rows or banks of different heights as is usual, there being four banks of keys in the present case.

As stated, the type bars are adapted to be elevated into a position for use by the elevation of the rest 11. With the type bars having a pin and slot or direct connection with their sub-levers, it was found to be necessary in order to enable the parts to move freely during the expansion of the machine and to prevent cramping or binding, to provide a yielding fulcrum or shiftable supporting means for the sub-levers. In the present instance such means is afforded by individual fulcrum arms 57, one for each sub-lever 46. The fulcrum arms, which are nearly upright when the machine is in collapsed condition, are provided each at its upper end with an open-mouthed slot indicated at 58 which receives a headed fulcrum pin 59 projecting laterally from the side of the associate operating lever 46 between its ends and resting in the bottom of the slot, there being thus provided a fulcrum for the lever 46. The fulcrum arms 57 are pivotally supported at their lower ends on an arcuate pivot wire 60 common to all of the fulcrum arms, and mounted on a detachable bar or member 61 which is segmental in shape and comprises a forward plate-like portion 62 and a thicker rear portion 63, the rear portion being formed with radial guide slots indicated at 64 in which the fulcrum arms 57 are received. Said portion 63 is also provided with a horizontal open-mouthed slot indicated at 65 in which the wire 60 is seated. The plate-like part 62 of the bar 61 rests on the top of the stationary segment 5 and is detachably secured thereto by headed screws 66, the heads of said screws being received in countersinks indicated at 67 on the top of the plate 62. The rear portion of the segment 5 is depressed or stepped down so that the under face of the portion 63 of the bar 61 may rest on it. The construction is such that when the screws 66 are threaded into place and tightened the detachable fulcrum member 61 is rigidly connected to the frame segment 5. There is thus provided a bearing member for the entire set of fulcrum arms which is detachable and attachable independently of

the type bar segment, thus promoting convenience in manufacturing and assembling. The casting 3 and the member 61 constitute a two-part support for the type bars and the sub-levers. The guide slots 64 are radially formed and have the same center as the slots 38 in the segment 4, the two sets of slots being aligned with each other as clearly appears from Fig. 1. It is to be understood that while for convenience of illustration the full showing of the slots 64 has been omitted from the drawings yet there is a complete series of said slots extending from one side to the other of the member 61, said slots corresponding in number to the slots 38 in the segment 4. It will be seen that the type bars together with part of their type actions comprising the levers 46, radiate from a common center, while the key levers extend fore-and-aft of the machine in substantial parallelism, although slightly fanned outward at the sides of the system in order properly to space the keys in the keyboard. Also it will be apparent that the links 48 may be bent or twisted in order properly to connect the sub-levers 46 with their key levers. Each type action is provided with separate spring restoring means that may comprise a coiled spring 68 hooked at its upper end in a hole in the associate sub-lever 46 back of the fulcrum thereof, said spring extending downward and being anchored at its lower end to an arcuate spring plate 69. Said plate is suitably secured to the under face of the segment 5 and has its inner edge portion 70 inclined upward and rearward and formed with a series of holes through which the lower ends of the springs 68 are hooked. The plate-like part 62 of the member 61 has suitably secured to its top a horizontal plate 71 which is also arcuate in shape and is inclined upward at its inner edge to provide a stop or support for the sub-levers 57 when the machine is in use, said sub-levers having movements which may be said to be more or less fore-and-aft or horizontal during the expansion and compaction of the machine, as distinguished from the vertical shifting movements of the rest 11 or lifting device. The forward edge portion of the plate 71 is adapted to serve as a locking device, preventing operation of the type actions when the machine is compacted as in Fig. 3, a shoulder or hook 48^a on each link 48 contacting at this time with the plate 71 so as to prevent downward movement of the link if it be attempted to depress its associate key lever.

It will be understood that when the machine is compacted as in Fig. 2 the poppet stud 29 is engaged with the forward of the two holes 33, thus setting the toggle elements 22 and 24, and the lifter 11-15 in depressed position with the type bars re-

4

cumbent and locked against operation by the plate 71. When it is desired to expand the machine for use, the poppet 29 is pulled out of engagement with the forward hole 33 and the crank arm 26 is swung rearward until the poppet is brought opposite the rear hole 33, the poppet then being released to engage in said hole and re-lock the parts. This rearward movement of the crank arm 10 rocks the shaft 25 and straightens the toggles as in Fig. 2 causing the lifter to be moved or shifted vertically upward on its trackways and swinging the type bars upward and rearward on their pivots 39 into 15 position for use. It will be observed that this swinging movement of the type bars is wholly pivotal as distinguished from a bodily movement, the pivotal support of the type bars being fixed. From Fig. 2 it will 20 be noted that while the type bars have not been brought to an exactly vertical position yet they are substantially upright and are supported by the rest 11 above their pivots in position to be actuated to print 25 when the key levers 50 are depressed. The raising or elevation of the type bars and the consequent expansion of the machine are permitted by reason of the fact that the fulcrums of the levers 46 are floating or yieldingly mounted so that said levers 30 may all simultaneously move or yield to the shifting of the type bars, these movements carrying said levers from the Fig. 3 position radially outward to the Fig. 2 position. The levers 46 near the middle of the machine will have a substantially forward 35 movement. While the motions of the outer levers of the series will include lateral or sidewise components, yet to a considerable 40 extent their movement is also forward. The fulcrums 59 of the levers or sub-levers 46 also move forward and at the same time are slightly lowered, due to the fact that the fulcrum arms 57 swing downward from a 45 substantially upright position to the inclined position illustrated in Fig. 2. This forward movement of the sub-levers swings the upper end portions of the links 48 forward about their pivotal connections 49, the 50 latter remaining stationary, and such swinging movement clears the locking shoulders 48^a from the locking plate 71, thus unlocking the type actions.

When one of the printing key levers 50 is depressed the parts of the type action will be moved from the Fig. 2 position to the position illustrated in Fig. 4, the link 48 pulling down the forward arm of the sub-lever 16 and raising the rear arm thereof, causing the actuating pin 45 to traverse 55 the cam slot 44 and swing the type bar downward with an accelerating motion due to the relationship of the pin-and-slot connection between the type bar and its sub-lever. Such accelerating action continues 60

until the type bar is within an inch or so of the platen and the pin has approached the end of the slot 44 and the type bar pivot 39, after which the pin begins to recede from the type bar pivot. The accelerating action is similar in results to that of the No. 10 Remington machine type bar action. With the parts related as in Figs. 2 and 4, the platen at this time is in its forward or lower case position and the inner or lower case type on the type bar will make the imprint. It will be understood that to print in upper case the platen is shifted rearward to the dotted line position of Figs. 2 and 4 and that this case shifting movement of the platen is entirely distinct from and independent of the shifting movements for compacting and expanding the machine. It is further to be noted that during the printing actuation of the type bar the bodily location of the fulcrum arm 57 will remain unaltered, said arm remaining in contact with the plate 71. On releasing the depressed printing key the type action will be restored to normal position by the spring 68.

The machine is compacted or compressed and the type bars simultaneously restored from the position of use (Fig. 2) to the position of disuse (Fig. 3) by manipulating the finger piece or key 31, swinging the crank arm forward again and raising the toggles 22, 24, lowering the lifter 11—15 and causing the type bars to slide down from the raised position to their lower or recumbent position.

Various changes may be made without departing from my invention.

What I claim as new and desire to secure by Letters Patent, is:—

1. In a collapsible typewriting machine, the combination of a set of type bars, means for actuating the type bars comprising a set of sub-levers, and means for expanding the machine for use by simultaneously swinging the type bars on their pivots to a new position and at the same time bodily shifting said sub-levers, said expanding means comprising a type bar rest settable in a plurality of positions.

2. In a collapsible typewriting machine, the combination of a set of type bars, a fixed support on which said type bars are pivotally mounted, means for actuating the type bars comprising a set of sub-levers having shiftable pivots, and means for expanding the machine for use by pivotally moving all of the type bars and at the same time automatically shifting said sub-levers and their pivots.

3. In a collapsible typewriting machine, the combination of a platen shiftable to change case, a set of type bars each provided with two types, one type on each type bar co-operating with the platen in one

of its shift positions and the other type co-operating with the platen in the other of its shift positions, a fixed segment on which said type bars are pivoted, means for actuating said type bars comprising a set of shiftable sub-levers, and means for expanding the machine for use by moving all of the type bars on their pivots simultaneously and at the same time bodily shifting said sub-levers.

4. In a collapsible typewriting machine, the combination of a platen shiftable to change case, a set of type bars each provided with two types, one type on each type bar co-operating with the platen in one of its shift positions and the other type co-operating with the platen in the other of its shift positions, a fixed segment on which said type bars are pivoted, means for actuating said type bars comprising a set of shiftable sub-levers, and means for expanding the machine for use by moving all of the type bars on their pivots simultaneously and at the same time bodily shifting said sub-levers, said last recited means comprising a type bar rest settable by hand and against which the type bars are adapted to lie in both their collapsed and expanded positions.

5. In a collapsible typewriting machine, the combination of a set of type bars, a fixed support on which said type bars are pivotally mounted, means for actuating the type bars comprising a set of sub-levers having shiftable pivots, and means for expanding the machine for use by pivotally moving all of the type bars and at the same time automatically shifting said sub-levers and their pivots, said last recited means comprising a type bar rest settable by hand and against which the type bars are adapted to lie in both their collapsed and expanded positions.

6. In a typewriting machine, the combination of a platen shiftable to change case, a set of type bars each provided with a plurality of types, one of which is adapted to co-operate with the platen normally, and the other with the platen when it is shifted, key operated means for actuating said type bars, comprising a set of sub-levers, means for shiftable supporting said sub-levers, and means comprising a shiftable type bar rest for simultaneously moving said type bars on their pivots to a new position and at the same time automatically shifting said supporting means for said sub-levers.

7. In a typewriting machine, the combination of a set of type bars, key operated means for operating said type bars comprising a set of sub-levers, swinging fulcrum arms on which said sub-levers are pivotally

supported, and means for moving said type bars and automatically swinging said fulcrum arms to shift the pivots of said sub-levers, said means comprising a hand-controlled type bar rest.

8. In a typewriting machine, the combination of a set of type bars; sub-levers having pin-and-slot connections with said type bars; pivoted fulcrum arms each providing a pivotal support for one of said sub-levers; key levers; links connecting said key levers with said sub-levers; and means for moving said type bars and simultaneously swinging said fulcrum arms to shift the pivots of the sub-levers, said means comprising a rest for supporting the type bars between their pivots and their type ends when said type bars are in collapsed position, a finger piece or key, and connections between said key and said type bar rest for shifting it to expand the machine for use.

9. In a top strike machine, the combination of a platen shiftable to change case; a set of type bars each provided with two types, one co-operative with the platen normally and the other when the platen is shifted; sub-levers having pin-and-slot connections with said type bars; pivotally mounted fulcrum arms on which said sub-levers are fulcrumed; key levers; links connecting said key levers with said sub-levers; and means for moving said type bars and simultaneously shifting said fulcrum arms, said means comprising a rest for supporting the type bars between their pivots and their type ends when said type bars are in collapsed position, a finger piece or key, and connections between said key and said type bar rest for shifting it to expand the machine for use.

10. In a typewriting machine, the combination of a type bar support formed with radial slots, a set of type bars seated in said slots, key levers, connections between said key levers and said type bars comprising sub-levers, fulcrum arms for said sub-levers, a second support provided with radial slots in which said fulcrum arms are seated, the slots in the two supports radiating from a common center, and means for detachably fixing said second support to said type bar support.

Signed at Syracuse, in the county of Onondaga, and State of New York, this 14 day of March, A. D. 1922.
